UNITED STATES PATENT OFFICE.

IRVING B. CRANDALL, OF EAST ORANGE, NEW JERSEY, AND MARION S. ESTES, OF NEW YORK, N. Y., ASSIGNEES TO WESTERN ELECTRIC COMPANY, INCORPORATED, OF NEW YORK, N. Y., A CORPORATION OF NEW YORK.

HIGH-FREQUENCY SOUND SIGNALING.

Application filed November 25, 1919. Serial No. 340,471.

This invention relates to high frequency sound signaling and more particularly to devices used in submarine signaling for receiving high frequency sound and producing indications therefrom.

An object of the invention is to provide selective means for receiving high frequency sound energy.

Another object of the invention is to provide a microphone receiver for receiving and responding to sounds of ultra-audible frequency.

An additional object of the invention is to provide a microphone mechanically tuned to sound energy of a given high frequency.

A further object of the invention is to provide a microphone capable of responding to high frequency sound waves in water.

A still further object of the invention is to provide a receiving system for high frequency submarine sound transmission.

According to this invention a solid back microphone is constructed with a carbon movable front electrode which may be spherical. The movable electrode is rigidly fixed to a thick metal diaphragm of such dimensions as to have a natural period corresponding to that of the high frequency sound waves to be received. The tuned microphone so designed acts to produce high frequency variations in an electric current passing therethrough and these high frequency electric current variations are detected in well known manner.

Referring to the drawing, Fig. 1 illustrates diagrammatically a high frequency submarine sound-receiving arrangement; Fig. 2 illustrates in section a tuned microphone receiver; Fig. 3 a section of a microphone; and Figs. 4 and 5 illustrate modified forms of the tuned diaphragm employed in the construction of Fig. 2.

In the receiving system of Fig. 1, a high frequency microphone receiver 1 is shown in circuit with a source 2 of unidirectional current and the primary winding of a transformer 3, the secondary winding of which is in the input circuit of a detector 4 of high frequency electrical currents. This detector is preferably of the thermionic discharge type. Associated with the input cir-

cuit of the detector by means of a transformer 5 is a local source 6 of high frequency electric currents which may be of the same frequency as that of the sound waves to be received, as in the case of telephony; or may be of a different frequency as in telegraphic or teledynamic control transmission. The output circuit of detector 4 is connected in well-known manner to an amplifier 7 by which low frequency currents resulting from the detecting action are amplified and supplied to a receiver 8 connected thereto.

In operation, the high frequency sound waves in water or other medium in which the microphone receiver is placed, impinge upon the diaphragm of the receiver and cause the microphone to set up corresponding high frequency variations in the microphone current supplied by source 2. Accordingly a high frequency electromotive force corresponding in intensity and frequency to the sound waves is induced in the secondary winding of transformer 3 and is impressed upon detector 4. Simultaneously therewith, a high frequency electromotive force is impressed upon the detector by local source 6. If heterodyne operation is to be employed the frequency of source 6 will be made different from that of the incoming sounds. For telephony, as explained in United States Patent No. 1,330,471, patented February 10, 1920 to B. W. Kendall for high frequency signaling, the current produced by the local generator will preferably be of the same frequency as the incoming sound waves. The detector 4 acts to combine the two electrical waves to produce in the output circuit a low frequency current component corresponding, in the case of heterodyne operation, to the beat difference note of the two electromotive forces supplied, and in the case where the local source 6 produces currents of the incoming wave frequency, telephonic or other low frequency modulations of the incoming sound waves. In either case the resultant low frequency current component is amplified by amplifier 7 and supplied to the receiving instrument, illustrated in Fig. 1 as a telephone receiver 8, but which may, however,

be any signal receiving or indicating device or in the case of teledynamic control transmission, a selecting or controlling element.

As shown in Fig. 2 illustrating the tuned microphone receiver, a microphone casing 9 of conducting material, has secured therein by means of insulating material 10, such as wax or rubber, a stem portion of a solid back member 11 of a microphone. The front electrode or button 12 of the microphone is attached by means of a screw 13 to tuned diaphragm 14 which is preferably of disc shape and is clamped against an annular seat by means of clamping ring 16 and bolts 17, attaching said ring to the seat portion of the casing. Conducting leads 18 are introduced into the casing 9 through an insulating sleeve 19 passing axially through a threaded bushing 20 of insulating material 21 fitted in a threaded recess in the casing. One of the leads is electrically connected to the casing and the other to the stem of the back member of the microphone, so that current supplied will pass from one lead through the casing, the diaphragm and the button and back member of the microphone to the other lead.

The microphone is shown in more detail in Fig. 3. The back member 11 comprises a stem and a cup-shaped portion 21 exteriorly threaded to receive an annular cap member 22. Clamped between cap 22 and the cup 21 is a thin flexible insulating washer 23, preferably of mica. The front electrode 12, which may be of carbon, is preferably spherical but may be of any compact shape insuring rigidity and fits into a central opening of washer 23, to which it is attached by glue or other adhesive material 25. Cup 21 is fitted interiorly with a cylindrical insulating member 26 and inside of this cup and adjacent its back wall a thin carbon disc 27 and a metallic disc 28 are placed. Carbon granules 24 of semi-globular or of the ordinary form are placed within the cup 21 and are retained by washer 23. The front electrode 12 bears against the granules and because of its shape produces large variations in pressure for slight displacements of the diaphragm.

The diaphragm 14 may be a plane disc, as shown in Fig. 2, or may be recessed, as indicated in Figs. 4 and 5. For high frequency operation the microphone receiver may be made selective of a particular frequency by so designing the diaphragm that it is mechanically tuned to the desired frequency. In accordance with the well known laws of tuning of clamped plates the frequency of the diaphragm may be made high by increasing its stiffness and decreasing its mass. Consequently, material of low atomic mass such as aluminum, may be used, and the diaphragm may be made relatively thick in proportion to its diameter.

In the modifications of Figs. 4 and 5 the diaphragm is shown centrally recessed so that the thickness at the center is considerably less than at its periphery. The recessing of the diaphragm appears in practice to give an effect corresponding to an increase of the ratio of its stiffness to its mass.

The front electrode 12 is rigidly attached to the tuned diaphragm and is made rigid and compact so that the electrode will be forced to partake of the high frequency movement of the diaphragm, and the variations in the microphonic current will correspond in frequency and in amplitude to the sound wave energy received.

In practice, operating at a frequency of 80,000 cycles per second, the diaphragm has been made of aluminum, the clamping ring having an internal diameter of an inch. With the form of diaphragm shown in Fig. 4, the minimum thickness of the diaphragm was made one-eighth of an inch, and the thickness at the periphery one-quarter of an inch. The front electrode was a spherical carbon ball five-sixteenths of an inch in diameter.

It is to be understood that the specific circuit and structural details, as well as the dimensions recited herein, are given merely by way of example of a construction which has been found satisfactory in practice, and that the invention is not to be limited thereto, but only by the scope of the appended claims.

What is claimed is:

1. An acoustical diaphragm comprising a disc the thickness of which varies symmetrically with respect to its center, said disc being composed of material of such atomic mass relatively to its diameter and thickness that, when clamped at its periphery, it substantially exclusively vibrates at a single superaudible frequency.

2. A tuned high frequency acoustical diaphragm comprising an aluminum disc substantially thinner at its center than at any other point and which has a generally lens-like form.

3. A tuned high frequency acoustical diaphragm comprising a disc, the thickness of which decreases progressively from its periphery towards its center.

4. An acoustical diaphragm comprising a disc whose thickness varies symmetrically with respect to its center and is minimum at the center, the atomic mass relatively to the diameter and thickness of said disc being such that, when clamped at its periphery, it vibrates substantially exclusively at a single superaudible frequency, and means for clamping said disc at its periphery.

5. A high frequency solid back microphone comprising a substantially spherical conducting button, a diaphragm, means for clamping said diaphragm near its periphery,

and a rigid connection between said button and said diaphragm, said diaphragm comprising a disc, whose atomic mass relative to its physical dimensions is such that it is 5 tuned at a definite superaudible frequency.

6. A solid back microphone comprising a cup containing granular conducting material, a substantially spherical conducting button, a thin flexible retaining member attached to said button and serving to close said cup, means insulating said button from said cup except through said granular material, a tuned diaphragm rigidly connected to said button, and terminal elements attached to said button and said cup whereby a circuit may be completed therebetween and through said granular material.

7. A solid back microphone sound receiver comprising a casing, a cup containing granular material rigidly attached thereto, a conducting button having a substantially spherical surface in engagement with said materi-

al, means insulating said button from said cup except through said granular material, a tuned diaphragm rigidly connected to said button, and terminal elements attached to said button and said cup whereby a circuit may be completed therebetween through said granular material.

8. A solid back microphone sound receiver comprising a rigid casing member having a front opening, a diaphragm closing said opening, a microphone carried thereby and secured at the back of said casing member, and means whereby said diaphragm may actuate said microphone, said diaphragm being of such atomic mass and relative dimensions to be tuned to a definite superaudible frequency.

In witness whereof, we hereunto subscribe our names this 19th day of November, A. D. 1919.

IRVING B. CRANDALL.
